United States Patent Office

Des. 183,343
Patented Aug. 12, 1958

183,343

LOUDSPEAKER CABINET

Robert W. Fuldnar, New York, N. Y., assignor to Electro-Voice, Incorporated, Buchanan, Mich., a corporation of Indiana

Application July 26, 1957, Serial No. 47,098

Term of patent 14 years

(Cl. D26—14)

Fig. 1.

Fig. 2.

Fig. 4.

Fig. 3.

Figure 1 is a perspective view of a loudspeaker cabinet, showing my new design;

Figure 2 is a side elevational view to a reduced scale;

Figure 3 is a plan view to a reduced scale; and

Figure 4 is a rear elevational view to a reduced scale.

The side of the loudspeaker cabinet opposite that shown in Figures 1 and 2 is a mirror image of the side shown in Figures 1 and 2.

I claim:

The ornamental design for a loudspeaker cabinet, as shown.
